UNITED STATES PATENT OFFICE.

CHARLES H. HOBBS AND TIMOTHY P. WHELAN, OF SLATERSVILLE,
RHODE ISLAND.

LEASE-ROD FOR LOOMS.

SPECIFICATION forming part of Letters Patent No. 401,351, dated April 16, 1889.

Application filed October 23, 1888. Serial No. 288,909. (No model.)

To all whom it may concern:

Be it known that we, CHARLES H. HOBBS and TIMOTHY P. WHELAN, of Slatersville, county of Providence, State of Rhode Island, 5 have invented an Improvement in Lease-Rods for Looms, of which the following description, in connection with the accompanying drawings, is a specification, like letters on the drawings representing like parts.

10 In the manufacture of cloth upon looms the warp between the harnesses and the roll or beam immediately above the let-off is separated into layers by means of what is known as a "lease-rod." This rod is usually composed of a bar oval in cross-section.

15 In accordance with our invention we have provided a lease-rod which is expansible or so constructed that it normally exerts tension upon and keeps the warp-threads strained between the roller or other beam above the warp-beam and the crossing of the warps at the rear of the harnesses or the reed.

20 Our invention consists, essentially, in an expansible lease-rod composed of two bars hinged or jointed together at their edges and combined with a spring, as will be described.

25 Figure 1 shows one of our improved expansible lease-rods in position in a warp supposed to be on its way to the harnesses to be woven into cloth. Fig. 2 is a front view of the lease-rod without the warps; and Fig. 3 is a modification, to be described.

30 Our improved expansible lease-rod as herein shown is composed of two bars, *a* *b*, which in the form in which our invention is herein 35 illustrated are connected together along one edge by hinges *c* *c*; the pintle connecting the halves of the said hinges being composed of a spring-wire, *d*, having its ends *d'* *d''* extended to bear respectively upon the bars *a* *b*. The 40 said pintle constitutes a spring which normally acts to separate the two bars; but, instead of making the spring also serve for a pintle, we may apply a spiral spring, as *e*, to the rod *f*, connected with the bar *b*, the ends 45 of the spring resting, respectively, against the bars *a* *b*. That end of the rod *f* which is not connected to the bar will be provided with a

shoulder or projection, as *f'*, to act as a limiting-stop to control the extent of separation of 50 the two members of the lease-rod.

In Fig. 1 the full and dotted lines show the lease-rod in different positions that it assumes during the operation of the loom, the lease-rod closing upon itself more or less as the 55 reed meets the fell of the cloth, the extent of closing movement of the lease-rod depending upon the blow of the reed and the tension exerted upon the warp. As soon as the reed retires from the fell of the cloth the spring 60 which controls the separation or expansion of the lease-rod acts to take up any undue slack in the warps *w*.

In the drawings, *r* is supposed to represent a roll or bar or a whip roll above an ordinary 65 let-off or warp-beam; or it might be a warp-beam, provided the lease-rod was to be used in a warping-machine.

The end of the bar *b* is extended and provided with holes *h* in order that the lease-rod 70 may be retained in any usual position substantially at right angles to the movement of the warp through the loom or warping machine.

We do not desire to limit our invention to 75 the exact construction of our expansible lease-rod, as the same may be variously modified, as will be apparent to any mechanic, so that the two main parts thereof will contract and then expand according to the amount of tension put upon the warp-threads between 80 which the lease-rod is placed and held.

We claim—

The two bars hinged together at their edges to form a lease-rod and a spring to normally 85 separate the said bars to act upon the warp-threads, substantially as described.

In testimony whereof we have signed our names to this specification in the presence of two subscribing witnesses.

C. H. HOBBS.
TIMOTHY P. WHELAN.
